(57) **CLAIM**

The ornamental design for a wireless irrigation transmitter, as illustrated and described.

DESCRIPTION

FIG. 1 is an isometric view taken from the front of the wireless irrigation transmitter;

FIG. 2 is an isometric view taken from the rear of the wireless irrigation transmitter;

FIG. 3 is a front elevation view of the wireless irrigation transmitter;

FIG. 4 is a rear elevation view of the wireless irrigation transmitter;

FIG. 5 is a right side elevation view of the wireless irrigation transmitter;

FIG. 6 is a left side elevation view of the wireless irrigation transmitter;

FIG. 7 is a top plan view of the wireless irrigation transmitter; and,

FIG. 8 is a bottom plan view of the wireless irrigation transmitter.
